CLAIM

The ornamental design for a hand-held data collector with removable scanner, as shown and described.

DESCRIPTION

FIG. 1 is an isometric view of the hand-held data collector with removable scanner.

FIG. 2 is a front view of the hand-held data collector with removable scanner of FIG. 1.

FIG. 3 is a rear view of the hand-held data collector with removable scanner of FIG. 1.

FIG. 4 is a right side view of the hand-held data collector with removable scanner of FIG. 1.

FIG. 5 is a left side view of the hand-held data collector with removable scanner of FIG. 1.

FIG. 6 is a top view of the hand-held data collector with removable scanner of FIG. 1; and,

FIG. 7 is a bottom view of the hand-held data collector with removable scanner of FIG. 1.

The broken lines showing portions of the hand-held data collector with removable scanner are included for the purpose of illustrating environmental structure and form no part of the claimed design.
